UNITED STATES PATENT OFFICE.

GEORGE DAVIDSON, OF BRITANNIA BEACH, BRITISH COLUMBIA, CANADA.

DEVICE FOR PULLING ROCK-DRILLS WHEN STUCK.

1,339,024.

Specification of Letters Patent.

Patented May 4, 1920.

Application filed August 9, 1919. Serial No. 316,358.

To all whom it may concern:

Be it known that I, GEORGE DAVIDSON, a subject of the King of Great Britain, and a resident of Britannia Beach, in the Province of British Columbia, Canada, have invented certain new and useful Improvements in Devices for Pulling Rock-Drills When Stuck, of which the following is a specification.

10 My invention relates to improvements in devices for pulling rock drills when stuck, and the object of my invention is to provide a simple and practical means whereby such drills may be drawn out of a hole when 15 stuck therein during the drilling process in a much quicker and more convenient manner than is possible under the present practice.

I attain this object by the construction 20 illustrated in the accompanying drawings in which—

Figure 1 is a side elevation of my device.

Fig. 2 is a plan view.

Similar figures of reference indicate similar parts throughout the views.

1 indicates an exteriorly threaded cylinder having a smooth bore adapted to slidably fit the drill 2, the lower end of the cylinder being plain, as at 3, and provided 30 with spikes or feet 4. 5 indicates a sleeve consisting of connected upper and lower boxes 6 and 7, the lower one of which is threaded internally correspondingly to the threaded cylinder 1 while the upper box 35 6 is adapted to fit the drill and is provided with three projections 8 which fit three corresponding grooves 9 in the drill body, which has normally four grooves, a groove 10 being formed in the box 6 designed to 40 register with the fourth drill groove when the projections 9 are in engagement with the other drill grooves. Both boxes 6 and 7 are squared on their outer sides so that a handle 11 may be placed on either of them, 45 as desired.

The manner in which the device is used may be briefly described as follows. Ordinarily when a drill becomes stuck in a hole during the drilling operation it is a difficult matter to draw it out but with the device 50 just described it may be pulled with great facility and ease. To effect this the assembled device is placed over the drill and slid along the same to the face of the rock, as shown in Fig. 1, and a key 12 is inserted 55 into the unoccupied groove of the drill and the groove 10, thus firmly uniting the sleeve and the drill. The handle 11 is then placed on the box 6 or 7 as desired, and the sleeve rotated in the direction necessary to unthread the box 7 off the cylinder, thus causing the box to rise thereon and consequently raising box 6 and therefore the drill 2, the turning operation being continued until the 60 drill is free.

From the foregoing it will be seen that I have devised a simple means whereby rock drills may be readily pulled from holes in which they have become stuck during drilling operations.

What I claim as my invention is—

A device for pulling grooved rock drills when stuck, comprising an externally threaded cylinder provided with anchoring prongs at its lower end and through which the upper end of the drill extends, a sleeve threaded at its lower end on said cylinder having its bore at its upper end restricted to fit the said drill and provided with projections entering all but one of the grooves 80 in the drill and with a groove registering with the remaining drill groove, a removable key fitting in the registering grooves of the sleeve and drill, and a handle adapted to be mounted on either end of said sleeve. 85

Dated at Vancouver this 23 day of July, 1919.

GEORGE DAVIDSON.
